HARRY WILSON AND MICHAEL A. LYNCH, OF WASHINGTON, DISTRICT OF COLUMBIA, ASSIGNORS TO UNITED STATES ORDNANCE COMPANY, OF WASHINGTON, DISTRICT OF COLUMBIA, A CORPORATION OF VIRGINIA.

PERCUSSION-FUSE FOR EXPLOSIVE PROJECTILES.

No. 807,006.

Specification of Letters Patent.

Patented Dec. 12, 1905.

Application filed September 23, 1903. Serial No. 174,356.

To all whom it may concern:

Be it known that we, HARRY WILSON and MICHAEL A. LYNCH, citizens of the United States, residing at Washington, District of Columbia, have invented certain new and useful Improvements in Percussion - Fuses for Explosive Projectiles, of which the following is a full, clear, and exact description when taken in connection with the accompanying drawings, which form a part thereof, and in which—

Figure 1 is a longitudinal diametrical section of our fuse, showing the various parts in their inactive position. Fig. 2 is a similar view showing the various parts in the position assumed during flight. Fig. 3 is a similar view showing the various parts in the position assumed upon lateral retardation during flight of the projectile. Fig. 4 is a transverse section on the line *a a* of Fig. 1. Fig. 5 is a detail perspective view of the firing-hammer during flight. Fig. 6 is a fragmental diametrical section showing a modified construction of the firing-hammer and the centrifugal released securing means carried thereby. Fig. 7 is a detail perspective view of the firing-hammer illustrated in Fig. 6 during flight. Fig. 8 illustrates still another modified construction of the firing-hammer and the centrifugal released securing means carried thereby. Fig. 9 is a detail perspective view of the firing-hammer illustrated in Fig. 8 during flight.

Our invention relates to that class of fuses in which the percussion element is released only by centrifugal force such as is produced by the rotation of a projectile during flight and comprises improved means: (*a*) for preventing the explosion of the primer except upon retardation of the projectile during flight when discharged from a rifled gun; (*b*) for normally securing the primer-exploding means in inactive position; (*c*) for releasing said primer-exploding means during flight of the projectile; (*d*) for positively actuating the primer-exploding means upon a graze or lateral impact; (*e*) for maintaining the primer-exploding means released when centrifugal force ceases and in improved construction generally.

Referring to the drawings, A is the fuse-body having a powder magazine or chamber

B, the igniting charge being retained therein by the wad C, which is secured in place by crimping the fuse-body thereon, said fuse-body having an annular recess A' extending a short distance in its inner surface, and is beveled on its outer surface at A² to produce a suitable thinness for the purpose of crimping.

D is a plug secured in the fuse-body, having a stem D', carrying the igniting cap or primer E, and perforated at D² to permit the passage of the flame from the primer E to the magazine B.

F is a firing-hammer comprised of two segmental members F' F², loosely secured together by the bolt F³, which is of a length that its ends will constantly just touch the surface of the chamber of the fuse-body and has the enlarged head F⁴ and the nut F⁵. The segmental members F' and F² are provided with the counterbores F⁶ and F⁷, respectively. Interposed between the nut F⁵ and the base of the counterbore F⁶ is a spring F⁸, while a spring F⁹ of greater strength than the spring F⁸ is interposed between the base of the counterbore F⁷ and the head F⁴. The springs F⁸ and F⁹ normally keep the segmental members F' and F² firmly together, and the spring F⁹ being of greater strength than the spring F⁸ the segmental member F' will always be held against the surface of the fuse-body chamber irrespective of the position of said fuse-body. The springs F⁸ and F⁹ can

be so constructed as to have a limited compression, and thus limit the transverse movement of the members F' and F² to prevent binding of said members against the wall of the fuse-body when they fly apart under the influence of centrifugal force. The members F' and F² have integral therewith the flanges F¹⁰ and F¹¹, respectively, the latter of which forms a centrifugally-released securing means normally locking the firing-hammer in safe position, the flange F¹¹ abutting the stem D' of the plug D and serving to normally lock the firing-hammer against forward movement until said flange is moved transversely of the casing in unison with the member F², and thereby passed out of engagement with the stem D', thus rendering the firing-hammer free to move forward upon impact for the purpose of exploding the primer. The

member F² is provided with the right-angular extension F¹², normally covering the front face of the member F', said member F' being of less length than the member F² to permit 5 said members to register throughout when assembled. The extension F¹² carries the firing-point F¹³, said firing-point being located a distance beyond the long axis of the face of the firing-hammer. Retained between the 10 members F' and F² in suitable recesses on opposite sides of the longitudinal axis of the firing-hammer and parallel therewith are the cylindrical pieces F¹⁴ and F¹⁵. It will thus be obvious that the flange F¹¹ normally abuts 15 the stem D' and the firing-point F¹³ is out of alignment with the primer E. When the projectile is fired, however, and centrifugal force is set up in the members F' and F², the member F' remains firmly seated against the 20 surface of the fuse-body chamber, the member F² flies out as far as the wall of the fuse-body chamber will permit or as far as the degree of compression of the springs F⁸ and F⁹ will permit, as the case may be, the flange F¹¹ 25 passes out of engagement with the stem D', the firing-point F¹³ centers in the longitudinal axis of the fuse-body and alines with the primer, the cylindrical pieces F¹⁴ and F¹⁵ being on opposite sides of the center fly outwardly in opposite directions, interpose themselves between the members F' and F², and 30 permanently maintain said members in the position assumed under the influence of centrifugal force, and the firing-hammer is thus rendered operative with relation to the primer 35 upon retardation of the projectile during flight.

It will be apparent that the flanges F¹⁰ and F¹¹ can be dispensed with and the firing-point abutting the stem D' will normally retain the firing-hammer inactive.

K is a plunger formed of two cylindrical pieces of metal K' K², having their abutting ends fastened by the soft metal strip K³. The 45 piece K' is seated in the cylindrical recess K⁴ in the base of the fuse-body. The piece K² is provided at its outer end with a flange K⁵, extending to the wall of the fuse-body chamber and having a rounded or curved periphery K⁶.

The position assumed by the parts of the fuse on lateral impact during flight is illustrated in Fig. 3. The weights K' and K² being centered in the axis of the fuse and free 50 to move under the influence of a lateral force only at their inner ends such force will cause said pieces to knuckle at that point and necessarily increase their combined longitudinal extent, thus forcing the firing-hammer forward and exploding the primer. The rounded periphery K⁶ of the piece K² serves to form a frictionless bearing during such operation.

In the modified construction shown in Figs. 6 and 7, the segmental members of the firing-hammer are held together by springs

F¹⁶ and F¹⁷ of equal strength, and the bolt F¹⁸ is of a length just equal to the short axis of the firing-pin when in its normal position. Both flanges F²⁰ and F²¹ normally abut the 70 stem D³ to maintain the firing-hammer inactive. In other respects the construction of the firing-hammer is similar to that heretofore described.

In the modified construction shown in Figs. 8 and 9 the firing-hammer is formed of 75 two segmental members normally held firmly together in the manner heretofore described and having centrifugally-released securing-flanges F²² and F²³, normally abutting the stem D⁴ of the plug D⁵. Secured centrally 80 of the bolt F²⁴ is a pin F²⁵, terminating in the firing-point F²⁶ and normally lying in the longitudinal grooves F²⁷ and F²⁸ in the segmental members of the firing-hammer. A ring D⁶ is inserted and secured by crimping in the 85 stem D⁴ to partially cover the primer and is provided with an aperture or passage leading to the primer to constantly receive the firing-point F²⁹. In this construction the firing-hammer is constantly in line with the 90 primer, but is normally held against contact therewith by the flanges F²² and F²³, abutting the stem D⁴ and released by centrifugal force, throwing said flanges out of engagement 95 with the stem D⁴.

Having thus described our invention, what we claim as new, and desire to secure by Letters Patent, is—

1. In a percussion-fuse, the combination of a casing, a primer, a firing-hammer formed of spring-compressed members adapted to be moved transversely of the casing under the influence of centrifugal force, one of said members carrying a firing pin or point rigidly secured thereto and moving transversely 100 therewith and centrifugally-released securing means normally holding the firing-hammer in its inactive position.

2. In a percussion-fuse, the combination of a casing, a primer, a firing-hammer formed of spring-compressed segments adapted to be moved transversely of the casing under the influence of centrifugal force, one of said segments carrying a firing-pin or point rigidly secured thereto and moving transversely 110 therewith and centrifugally-released securing means normally holding the firing-hammer in its inactive position.

3. In a percussion-fuse, the combination of a casing, a primer, means for supporting the primer in the casing, a firing-hammer formed of spring-compressed members adapted to be moved transversely of the casing under the influence of centrifugal force, a firing pin or point carried by one of said 120 members and moving transversely therewith and means carried by the members normally retaining the firing-hammer against forward movement by engagement with the primer-supporting means and adapted to 125 130

telescope on said primer-supporting means upon impact when the members of the firing-hammer have been moved transversely under the influence of centrifugal force.

5 4. In a percussion-fuse, the combination of a casing, a primer, means for supporting the primer in the casing, a firing-hammer formed of spring-compressed members adapted to be moved transversely of the casing 10 under the influence of centrifugal force, a firing pin or point carried by one of said members and moving transversely therewith and a flange on one of said members normally retaining the firing-hammer against 15 forward movement by engagement with the primer-supporting means and adapted to telescope on said primer-supporting means upon impact when the members of the firing-hammer have been moved transversely under the influence of centrifugal force.

20 5. In a percussion-fuse, the combination of a casing, a primer having a fixed position in the longitudinal axis of the fuse, a firing pin or point constantly at right angles to the 25 transverse axis of the fuse and out of alignment with the primer and means operated independently of the shock of discharge for alining said firing pin or point with the primer.

30 6. In a percussion-fuse, the combination of a casing, a primer having a fixed position in the longitudinal axis of the fuse, a plunger, a firing pin or point constantly at right angles to the transverse axis of the fuse and out 35 of alignment with the primer and means operated independently of the shock of discharge for alining the firing pin or point with the primer.

40 7. In a percussion-fuse the combination of a casing, a primer, a firing-hammer formed of spring-compressed members adapted to be moved transversely of the casing under the influence of centrifugal force, one of said members carrying a firing pin or point rigidly secured thereto and moving transversely therewith and securing means normally locking the firing-hammer in safe position and unlocked by the transverse movement of the members of the firing-hammer.

45 50 8. In a percussion-fuse, the combination of a casing, a primer, a firing-hammer formed of spring-compressed segments adapted to be moved transversely of the casing under the influence of centrifugal force, one of said segments carrying a firing pin or point rigidly secured thereto and moving transversely therewith and securing means normally locking the firing-hammer in safe position and unlocked by the transverse movement of the segments of the firing-hammer.

55 9. In a percussion-fuse, the combination of a casing, a primer, a firing-hammer formed of spring-compressed members adapted to separate transversely of the casing under the influence of centrifugal force, one of said seg-

65 influence of centrifugal force, one of said members carrying a firing pin or point rigidly secured thereto and moving transversely therewith and centrifugally-released securing means normally holding the firing-hammer in safe position.

70 10. In a percussion-fuse, the combination of a casing, a primer, a firing-hammer formed of spring-compressed segments adapted to separate transversely of the casing under the influence of centrifugal force, one of said segments carrying a firing pin or point rigidly secured thereto and moving transversely therewith and centrifugally-released securing means normally holding the firing-hammer in safe position.

75 11. In a percussion-fuse, the combination of a casing, a primer, means for supporting the primer in the casing, a firing-hammer formed of spring-compressed members adapted to separate transversely of the casing 85 under the influence of centrifugal force, a firing pin or point carried by one of said members and moving transversely therewith and means carried by one of the members normally retaining the firing-hammer against 90 forward movement by engagement with the primer-supporting means and adapted to telescope on said primer-supporting means upon impact when the members of the firing-hammer have separated under the influence 95 of centrifugal force.

100 12. In a percussion-fuse, the combination of a casing, a primer, means for supporting the primer in the casing, a firing-hammer formed of spring-compressed members adapted to separate transversely of the casing under the influence of centrifugal force, a firing pin or point carried by one of said members and moving transversely therewith and a flange on one of said members normally retaining the firing-hammer against forward movement by engagement with the primer-supporting means and adapted to telescope on said primer-supporting means upon impact when the members of the firing-hammer have 105 separated under the influence of centrifugal force.

110 13. In a percussion-fuse, the combination of a casing, a primer, a firing-hammer formed of spring-compressed members adapted to 115 separate transversely of the casing under the influence of centrifugal force, one of said members carrying a firing pin or point rigidly secured thereto and moving transversely therewith and securing means normally locking the firing-hammer in safe position and unlocked by the separation of the members of the firing-hammer.

120 14. In a percussion-fuse, the combination of a casing, a primer, a firing-hammer formed of spring-compressed segments adapted to 125 separate transversely of the casing under the influence of centrifugal force, one of said seg-

ments carrying a firing pin or point rigidly secured thereto and moving transversely therewith and securing means normally locking the firing-hammer in safe position and 5 unlocked by the separation of the segments of the firing-hammer.

In testimony whereof we have signed our

names to this specification in the presence of two witnesses.

HARRY WILSON.
